UNITED STATES PATENT OFFICE.

EDWARD H. BINNS AND RALPH H. BINNS, OF PITTSBURGH, PENNSYLVANIA, AND WILLIAM A. DE HART, OF TEANECK, NEW JERSEY; SAID DE HART ASSIGNOR TO SAID EDWARD H. BINNS AND SAID RALPH H. BINNS, BOTH OF PITTSBURGH, PENNSYLVANIA.

FLEXIBLE CLOSURE.

Application filed February 18, 1925. Serial No. 10,061.

The present invention relates to improvements in the type of flexible closures having flexible strips or stringers carrying interlocking fastening devices and a sliding cam device for moving said fastening devices into and out of interlocking engagement. Forms of such a structure are shown in earlier applications, Ser. No. 682,022, filed December 21, 1923 and Ser. No. 724,355, filed July 5, 1924. The invention of the present application comprises an improved form of cam slider for operating the fastening devices, and an improved latching device for securing the slider against movement.

In order that the invention may be fully understood it will first be described with reference to the accompanying drawings and afterwards pointed out more particularly in the annexed claims.

In said drawings:

Figure 1 is a front elevation of a flexible closure embodying the present invention;

Figure 2 is a similar view showing the combined latch plate and pull member in open position extended above the slider;

Figure 3 is a similar view with the combined latch plate and pull member extended below the slider in position for opening the closure;

Figure 4 is an edge elevation of the device with the parts in the position shown in Figure 1;

Figure 5 is a similar view with the parts in the position shown in Figure 2;

Figure 6 is a lower end view of the slider in the position shown in Figure 1; and

Figure 7 is a detail plan view taken on the line 7-7 of Figure 6.

In the type of flexible closure to which the present invention relates, two flexible strips or stringers 1, 2 are formed at their inner edges with beads or thickened portions 3 upon which are secured interlocking fastening devices.

Each interlocking fastening device is preferably formed with a U-shaped yoke 10 embracing and compressed upon the beaded or thickened edge 3 of a flexible stringer, a narrow neck 12, a forked hook 13, and the opposite riding lugs or shoulders 15. The specific form and operation of the fastening devices of the preferred construction will be more fully understood by reference to

the above named application Ser. No. 724,355.

The operating cam slider is preferably constructed as set forth in the above named application Ser. No. 724,355 of a back-plate 20 and a fore-plate 21 mounted in spaced relation upon a binder post 22. The inner faces of the back-plate and fore-plate are provided with controlling grooves 25 separated by a central guide rib 26. The riding lugs 15 of the fastening devices operate in the controlling grooves 25.

It will be observed that the upper edges of the back-plate 20 and fore-plate 21 are cut out or recessed at 30 between the central longitudinal part of the slider and the outwardly flaring wings containing the diverging upper portions of the grooves 25. It will be understood that in the operation of the slider of this type upon the described fastening devices, the fastening devices are controlled in their movements into and out of locking engagement by the riding lugs 15 sliding in the grooves 25. The recesses 30 in the back-plate and fore-plate of the slider provide free space for the movement of the bifurcated hooks of the fastening devices as they are directed into the open upper ends of the slider channels. In effect the laterally diverging wings or sides of the back-plate and fore-plate containing the upper ends of the controlling grooves 25, are extended a little beyond the edge walls of their supporting members, thereby giving the controlling grooves a chance to get each fastening device under accurate control before the hooks can come in contact with an edge wall.

35 is a swivel plate freely pivoted upon a stud 36 seated in the fore-plate 21. This swivel plate 35 is hinged at 37 to the upper end of a combined latch plate and pull member 38, which is formed adjacent to its free end with a slot 39 to receive a spring lip 40 formed on the end of the swivel plate 35 opposite the hinge 37. This spring lip 40 engaging the wall of the recess 39 retains the latch and pull member in closed position upon the swivel plate.

The free end of the latch and pull member 38 is also provided with an inwardly presented bifurcated or two-part detent 45 adapted to straddle the lug 46 on the lower

edge of the fore-plate 21. This two-part detent 45 closes over the lower open ends of the grooves 25 of fore-plate 21 thereby intersecting the path of the outer riding lugs 15 of the fastening devices. In this way the detent 45 locks the slider against movement upon the interlocking fastening devices against either downward or upward displacement.

- 10 It will be observed that the detent of latch plate 38 engages the fastening devices while the latter are engaged or interlocked, so that the strain of the slider latch will be firmly resisted by the co-operative strength of the fastening devices. This arrangement entirely obviates the defect of some prior devices in which a slider locking device engages individual fastening devices in disengaged position. The bifurcated detent 45 in straddling the lug 46 serves to prevent lateral movement of the swivel plate 35 and the parts are held in this closed interlocking position by the engagement of the snap lip 40 with the member 38 at 39.

15 The improved slider having recessed upper edges to prevent interference with the interlocking members in the locking motion and the novel form of slider locking device 20 which cooperates with the riding lugs of the fastening devices are of importance in simplifying and improving the construction of this type of flexible closure.

25 It will be understood that the broad idea of the combined latch plate and pull member hinged to a swivel plate is covered by our above named application, Ser. No. 724, 355, but that the specific details of the improved form of this latch plate and pull member with its detent directly engaging interlocked fastening devices are claimed in the present case.

30 We claim:—

45 1. In a flexible closure or fastener, the combination with flexible stringers carrying spaced interlocking fastening devices formed with riding lugs or shoulders, of an operating slider formed with internal controlling grooves engaging said riding lugs or shoulders and thereby positively controlling the movements of the fastening devices, the upper edges of the slider walls being recessed and the grooved wall portions projecting beyond said recesses to control said fastening devices without interference with the slider walls.

50 2. In a flexible closure or fastener, the combination of flexible stringers carrying spaced interlocking fastening devices formed with riding lugs or shoulders, of an operating slider formed with a back-plate and fore-plate rigidly attached together in their central longitudinal plane and formed upon their inner faces with laterally diverging controlling grooves engaging said

riding lugs or shoulders, said back-plate and fore-plate being cut away or recessed in their upper edges between the diverging portion of said controlling grooves and the central longitudinal plane of the slider, to thereby avoid interference between the fastening devices and the slider.

55 3. In a flexible closure or fastener, the combination with flexible stringers carrying spaced interlocking fastening devices, of an actuating slider embracing and sliding upon said fastening devices for effecting their engagement and disengagement, a swivel plate pivoted upon said slider, and a latch plate hinged upon said swivel plate and formed with an inwardly presented detent adapted to engage the fastening devices in interlocked position.

60 4. In a flexible closure or fastener, the combination with flexible stringers carrying spaced interlocking fastening devices formed with riding lugs or shoulders, of an operating slider formed with controlling grooves engaging said riding lugs or shoulders, a swivel plate pivoted upon said slider, and a latch plate hinged upon one end of said swivel plate and formed with an inwardly presented detent adapted to be presented across the path of said riding lugs or shoulders.

65 5. In a flexible closure or fastener, the combination with flexible stringers carrying spaced interlocking fastening devices formed with riding lugs or shoulders, of an operating slider formed with controlling grooves engaging said riding lugs or shoulders, a swivel plate pivoted upon said slider, a latch plate hinged upon one end of said swivel plate and formed with an inwardly presented detent adapted to be presented across the path of said riding lugs or shoulders, and a catch between said swivel plate and said latch plate.

70 6. In a flexible closure or fastener, the combination with flexible stringers carrying spaced interlocking fastening devices formed with riding lugs or shoulders, of an operating slider formed with controlling grooves engaging said riding lugs or shoulders, a swivel plate pivoted upon said slider, a latch plate hinged upon one end of said swivel plate and formed with an inwardly presented detent adapted to be presented across said controlling grooves in the paths of said riding lugs or shoulders, and a catch upon said swivel plate engaging said latch plate for holding the slider in locked position.

75 7. In a flexible closure or fastener, the combination with flexible stringers carrying spaced interlocking fastening devices formed with riding lugs or shoulders, of an operating slider having a fore-plate and a back-plate formed with controlling grooves engaging said riding lugs or shoul-

ders, said slider fore-plate also having a central longitudinally projecting lug at one end between the controlling grooves, a swivel plate pivoted upon said slider, a latch plate hinged upon one end of said swivel plate and formed with an inwardly presented bifurcated locking detent adapted to embrace said lug to hold the swivel plate

against movement and project across said controlling channels in the path of the riding lugs or shoulders, and a catch upon said swivel plate engaging said latch plate. 10
